RETRACTABLE JAW WRENCH HAVING PARALLEL RESILIENT JAWS

Robert S. Clough, Wilmington, Del.

Application January 19, 1951, Serial No. 206,850

1 Claim. (Cl. 81—128)

1 This invention relates to new and useful improvements in a combined socket wrench and screw driver, and this application is a continuation-in-part of the copending application for patent, Serial No. 726,866, filed February 6, 1947, and now abandoned.

The basic object of this invention is to provide a tool whereby nuts and screw heads of various sizes may be engaged and held while tightening or loosening the same. The present tool is essentially comprised of a pair of jaws of special character movable into open and closed positions by reciprocable movement of the jaws outwardly and inwardly of a tubular body, and the instant form of the invention includes means for locking the jaws in position on a nut or screw head.

A particular object of the present invention is to provide a tool of the above-described type in which the work gripping jaws are resiliently urged apart but are so controlled as to constantly maintain a substantially parallel relationship to each other whereby a plurality of different sized nuts and screws may be gripped with equal facility.

Yet another object of the invention is to provide a tool of this character which is ideally adapted for use by mechanics and electricians handling equipment where nuts and screws are frequently located in positions making the use of ordinary tools difficult or impossible.

A specific object of the invention is to provide a fishing tool for screws which have previously been loosened by a screw driver, the present tool being ideally adapted for securing a firm grip on the loosened screw, thus facilitating the further unscrewing thereof and the removal thereof, and preventing the loss of the screw.

Another object of this invention is to provide a tool of simple and practical construction, which is efficient and reliable in operation, relatively inexpensive to manufacture and otherwise well adapted for the purposes for which the same is intended.

The tool of the present invention can be broadly described as comprising a manually reciprocable member mounted to slide within a tubular handle under the effect of a resilient motive means and carrying at one end a pair of work engaging jaws which are resiliently biased apart into contact with the wall of the handle. Each of the jaws is formed as an elongated finger member having an ogee curvature along its longitudinal axis and a transverse contour of substantially V-shape adjacent the free end thereof. The tubular handle is provided with a flared portion at one end for cooperation with the ogee curvature of the finger members in such manner that the finger members maintain a substantially parallel relationship to each other as they are extended from and withdrawn into the handle by sliding the manually reciprocable member. A lug is formed on each

2 finger member near its free extended end to provide a back-stop or rest against which nuts may be seated; or interchangeably, which may fit into the conventional kerf in screws.

It will be apparent that this construction provides a unique arrangement adapting the tool for use with nuts and screws of various sizes, and for both applying and removing the same in cooperation with a threaded connection. In this respect the flared portion of the handle and the ogee curvature of the finger members have different radii in order to maintain a parallel relationship between the gripping jaws when grasping a particular work component and to implement a rapid threading or unthreading operation without skewing or damaging the gripped component.

Other objects and advantages reside in the details of construction and operation as more fully hereinafter described, reference being had to the accompanying drawings forming part hereof, wherein like numerals refer to like parts throughout, and in which:

Figure 1 is a longitudinal sectional view;
Figure 2 is a fragmentary longitudinal sectional view, showing the jaws in a projected and open position;

Figure 3 is an end elevational view of the tool;
Figure 4 is an elevational view of one of the jaws removed from the tool;

Figure 5 is a view, largely in vertical section, showing the jaws in gripping engagement with a nut, together with contiguous portions of the tool;

Figure 6 is a similar view showing the tool in gripping engagement with a screw head; and
Figure 7 is another end view of the tool.

Similar characters of reference designate similar or identical elements and portions throughout the specification and throughout the different views in the drawing.

Referring now to the drawings in detail, wherein for purposes of illustration I have disclosed a preferred embodiment of the invention, the numeral 5 designates a tubular body having its one end flared as shown at 6 and having an enlargement 7 at the other end thereof, this enlargement being roughened or serrated to provide for non-slipping engagement with one end of a coaxial tubular handle 8. The tubular body 5 is preferably constructed of lightweight metal while the handle 8 may be constructed of plastic, hard rubber or other suitable material.

The inner end of the enlargement 7 on the body 5 is of a diameter less than the inside diameter of the handle 8, whereby there is provided a shoulder 9 against which one end of a coil spring 10 abuts, the other end of the spring abutting a push button or plunger 11 coaxially and slidably mounted in the end of the handle 8 remote from the body 5.

The plunger 11 is axially bored throughout a

portion of its length and internally threaded. A rod 12 has one end thereof threaded into the plunger, and this rod 12 extends longitudinally through the handle 8 and into the tubular body 5. To the other end of the rod 12 is pivotally attached the shank portions 13 of a pair of jaws 14, which shanks are preferably slightly resilient, the means of attachment including a pin 15 extending transversely through said other end of the rod 12 and through apertures provided on the inner ends of the shanks 13.

The jaws 14 extend longitudinally in the tubular body 5, in opposed relation with respect to each other, and the jaws are substantially V-shaped in cross section with the valleys of the jaws opposed to each other as clearly shown in Figure 3 of the drawings. The flared end 6 of the tubular body is shaped to provide V-shaped guides 17 at opposite sides of the body and in which the jaws 14 are conformably seated for frictional engagement with the guides 17 as the jaws are moved axially of the body 5.

As will be apparent from an inspection of Figs. 1, 2 and 4, each jaw 14 comprises an elongated finger member having an ogee curvature along its longitudinal axis, with the radius of curvature being different from that of the flared region 6 of the tubular handle. It will thus be appreciated that the jaws may be reciprocated to an extended position, as shown in Fig. 2, without causing a flaring of the jaws. This retention of a parallel alignment has been found to be of prime importance in adapting the tool for efficient operation on nuts and screws of widely varying sizes.

A lug 18 is struck inwardly from each of the jaws 14, adjacent the outer ends of the jaws, the lugs having each a straight transversely projecting edge 19 adapted for engagement in the kerf or groove 20 of a screw head 21. As will be apparent from the illustration in Fig. 4, each lug is formed by punching a section 18 of the jaw wall 14 and bending this section inwardly at the bottom of the V-shaped groove to present the straight edge 19 transversely of the jaw. The screw head will simultaneously be gripped by the jaws 14 and this construction provides for the turning of the screw by a similar turning movement of the body 5 and handle 8, and the screw will be held securely so that the same will not be lost during the unscrewing operation. The V-shaped construction of the jaws allows the jaws to conform with the sides of a nut 22, whereby the nut may be tightly gripped while being tightened or loosened. Of course, the fact that a bolt on which the nut is mounted extends a short distance beyond the nut is immaterial, since the instant device is adapted to accommodate such projecting end of the bolt.

In the operation of the device the jaws 14 may be projected outwardly at the end of the body, indicated at 6, by depressing the plunger 11 against the tension of the spring 12 and the jaws are held against the flared end 6 of the body by the action of a wire spring 23 which has a free end 24 bearing against the inside of one of the jaws. The other end 25 of the spring is engaged in an opening 26 in the shank 13 of the opposite jaw. The work, such as the screw head 21 or the nut 22 is engaged between the jaws and upon releasing the plunger 11 the jaws are retracted into tight gripping engagement by the spring 12. The plunger 11 has preferably an enlarged head 27. The head 27 carries radiating arms 28 compris-

ing handles whereby the plunger can be rotated relative to the rod 12. When a nut or screw head has been engaged by the jaws 14 and/or the lugs 18, the plunger 11 can be screwed onto the rod 12 so that the head 27 will engage a compressible washer 29 on the end of the handle 8, whereby the jaws 14 are preserved in gripping relation on the nut or screw head, this locking feature of the device being considered an important novel feature in this invention. The provision of a compressible washer 29 has been found to lessen the tendency for the plunger 11 to become seized on the end of the handle 8, and to generally improve the efficiency of the tool. Other bars 30 are provided in radiating relation on that end portion of the handle 8 remote from the jaws 14, these other bars 30 also comprising handle members. Finally, an insulating sleeve 31 is bonded to the exterior surface of the portion of the tubular body member 5, extending from the enlargement 7 to the flaring end of the body member. It should be noted that the insulating sleeve 31 and the insulating handle 8 further adapt this tool for use in electrical maintenance and similar work.

From the foregoing it will be obvious that a highly utilitarian tool for the purposes set forth has been provided in this invention, and further description would appear unnecessary.

Having described the invention, what is claimed as new is:

A tool comprising a tubular handle having an outwardly flared open end, a member mounted for manual reciprocation in said handle, resilient means cooperating with said handle and said member and normally urging said member to a retracted position, a pair of opposed gripping jaws carried by said member including means resiliently urging said jaws apart and into contact with the interior surface of said flared open end, each said jaw comprising an elongated finger having an ogee curvature along its longitudinal axis in substantially parallel relationship with said flared portion of said handle, the radii of curvature of said flared open end of said handle differing from the radii of curvature of said finger whereby the tubular handle functions as a guideway for camming said jaws together in opposed parallel relationship upon retracting said member, said finger further including a substantially V-shaped transverse contour, and a lug carried by each said finger whereby said jaws may serve to engage, grip and turn nuts and screws interchangeably.

ROBERT S. CLOUGH.
